A technical diagram of a structural frame component. It features a vertical post on the left labeled 'f' at the top and 'f'' at the bottom. A horizontal beam extends from the right side of the post, labeled 'd'. A diagonal brace extends from the top of the post to the right, labeled 'f'.

J' INVENTOR
F Francis G. Davis,
I by *J. M. Doolittle*
Attorney

UNITED STATES PATENT OFFICE.

FRANCIS G. DAVIS, OF WATERTOWN, NEW YORK, ASSIGNOR TO THE H. H. BABCOCK BUGGY COMPANY, OF SAME PLACE.

JUMP-SEAT VEHICLE.

SPECIFICATION forming part of Letters Patent No. 409,141, dated August 13, 1889.

Application filed May 16, 1889. Serial No. 311,037. (No model.)

To all whom it may concern:

Be it known that I, FRANCIS G. DAVIS, a citizen of the United States, residing at Watertown, in the county of Jefferson and State of New York, have invented certain new and useful Improvements in Vehicles; and I do hereby declare the following to be a full, clear, and exact description of the invention, such as will enable others skilled in the art to which it appertains to make and use the same.

My invention relates to shifting seats of vehicles of that class commonly known as "jump-seats," in which the vehicle is converted into one having one, two, or more seats, and in which when one seat only is used the others will be concealed from view.

The objects of my invention are to improve the construction of this class of vehicles in the matter of folding the seats, so as to effectually conceal from view when the vehicle is in one position certain features used when the vehicle is in other positions, to reduce to the minimum the number of parts necessary to perform such operation, and to thereby simplify and at the same time render more efficient the construction of the apparatus.

To these ends my invention consists of the arrangement of parts, as more fully herein-after described and particularly claimed.

My invention is illustrated in the accompanying drawings, in which—

Figure 1 is a side view in elevation showing the vehicle-body arranged for one seat only; Fig. 2, a similar view, partly in section, showing two seats back to back; and Fig. 3, a similar view with two seats fronting the same way.

Referring to the drawings, A represents the body of the vehicle, of any desired pattern and construction.

D is a double combination-hinge composed of a long arm E, having a knuckle at each end. The knuckle at the front end turns upon a pin f, having straps b' and d', also connected with said pin. The strap d' is bolted rigidly to the front end of the body, and the strap b' to the underside of the front seat. The knuckle of the arm E at the rear end is se-

cured to a pin g, with a strap F also connected to said pin g. These hinges, with their arms and straps, are in duplicate and used to raise and close both the front and its back, which back also constitutes the first rear seat.

B is the front seat, the bottom of which is secured to straps b' of hinge D. G, the back and first rear seat, is secured to straps F of said hinge.

H is a lazy-back secured by rods to the front end of the back and seat G.

I is a rear seat supported on a solid frame composed of front uprights K', rear uprights K², and bottom pieces K³, the front end of which frame is hinged at j to the railing K. The back uprights K² rest on the bottom of the vehicle.

L is a lazy-back secured by rods rigidly to the seat I.

The operation is as follows: When it is desired to arrange the parts, as shown in Fig. 1, with only a single seat and its back exposed to view, the back and seat G being turned up vertically, the front seat B and the seat G are turned up on the front hinge D, and the rear seat I is turned over on its hinge-support j and, together with the lazy-back L, is placed within the body A. The front seat and back G are then turned down. When it is desired to have the back G used as a seat, as shown in Fig. 2, the front seat B is raised and the back G is turned down on hinge F to a horizontal position, bringing the lazy-back H to a vertical position, and in that position the back G is supported by the frame-work composed of the uprights K' K² K³. In this position the two seats are back to back.

When it is desired to arrange the vehicle in the position shown in Fig. 3 from Fig. 2, with two seats fronting the same way, the front seat B is first raised to nearly a vertical position, rear seat G turned vertically, or nearly so, on rear hinges F, and then is further turned upward and forward on the front hinge D. The seat I is then raised and turned backward on its hinge-support j until it and the lazy-back L assume the position shown in said figure. The seat G is then turned back vertically, so as to bring the lazy-back H

within the box and under the front seat B, as shown in Figs. 1 and 3, and front seat B turned down over the same.

Having thus described my invention, what I claim is—

1. The combination, with a vehicle-body, of a front seat hinged to the front of said body and a rear seat and back also independently hinged to the front of said body, whereby said front and rear seat may be independently raised to a vertical or nearly vertical position, substantially as described.
2. In combination with a vehicle-body, the hinge D, composed of the straps b' d' and the arm E, the hinge F connected to said arm, the front seats connected to the straps b', the straps d' bolted to the body, and the rear seat and back G, secured to the hinges F, substantially as and for the purpose described.
3. The combination, with the vehicle-body, of the front and rear seat and back G, hinged independently to the front of the body, the hinge F, to which said seat G is also hinged, and the rear seat I, hinged to the vehicle at the rear of the body, whereby when the front seat and seat G are raised and turned up the said rear seat I may be turned under the front seat, substantially as described.

4. The rear seat I, in combination with a supporting-frame composed of front uprights K', rear uprights K², and bottom pieces K³, and the railing K, to which the uprights K' are hinged, while the rear uprights rest on the bottom of the vehicle, and the lazy-back L, rigidly secured to the seat I, substantially as described.

5. In combination with the body, the rear seat and back G, hinged to the front of the body, and the rear seat I, provided with the frame-work K' K² K³, whereby when the said seat G is lowered to a horizontal position and the rear seat L is folded within the body the seat G will be supported on said frame-work, substantially as described.

6. In combination with the vehicle-body, the front seat hinged to the front of said body, the rear seat and back G, also hinged to the front of the said body, and the lazy-back secured to the front end of said rear seat and back G, substantially as described.

In testimony whereof I affix my signature in presence of two witnesses.

FRANCIS G. DAVIS.
